UNITED STATES PATENT OFFICE.

CLARENCE A. VETTER, OF PITTSBURGH, PENNSYLVANIA, ASSIGNOR TO BEST ELECTRIC COMPANY, OF PITTSBURGH, PENNSYLVANIA.

SEPARABLE PLUG.

1,322,075.

Specification of Letters Patent. Patented Nov. 18, 1919.

Application filed August 7, 1916. Serial No. 113,511.

To all whom it may concern:

Be it known that I, CLARENCE A. VETTER, a resident of Pittsburgh, in the county of Allegheny and State of Pennsylvania, have 5 invented a new and useful Improvement in Separable Plugs, of which the following is a specification.

This invention relates to separable attachment plugs, such as are used for making connection from any portable electric device to a lamp socket, or other similar source of current. The object is to provide a separable plug embodying the usual body member and cap which, when coupled to each other are held securely, but which may be easily disengaged by an outward or lateral pull on the cap, without injury to the plug or detachment of the cords from their binding posts. A further object is to provide a separable attachment plug the members of which may be connected to each other by relative longitudinal movement, resulting in a secure locking together, but which may be easily disconnected by any withdrawing movement of the cap. A further object is to provide a separable attachment plug in which the contact members are simple in construction, integral with the base, rigidly attached thereto, or molded 20 therein. A further object is to provide a separable attachment plug in which the terminal members carried by the cap will form a spring-pressed contact with the terminal contact members carried by the base, and which will have means for engaging the two parts independent of the contact members, the contact members forming merely a wiping contact without any latch or positive engagement. Another object is to provide a separable attachment plug in which the base will be made of an enveloping material carrying merely metal contact strips; thus providing a device which can be manufactured very cheaply. Other objects and 35 advantages of the invention will be apparent to those familiar with such constructions.

Referring to the drawings, which show an embodiment of my invention, Figure 1 is a plan view of the base with the cap removed; Fig. 2 is a central vertical section through the cap and base in locked position, on the line 2-2 of Fig. 1; Fig. 3 is a central ver-

tical section, on the line 3-3 of Fig. 1, showing the locking arrangement; Fig. 4 55 is an elevation of the base, with the side contact exposed, the cap being in section; Fig. 5, is an under view of the cap; and Fig. 6 is an under view of the entire plug.

The plug comprises the usual body portions, a cap 1, and a base 2. These are made of any suitable insulating material, such as porcelain, hard rubber, or composition. But preferably they are of a material which may be easily molded. The cap has a central opening 3, adapted to receive the conductor cords, and carries metal terminal plates 4, secured thereto by means of screws 5. These members 4 carry binding posts 6, adapted to secure the ends of the usual conducting cords. Portions of the plate members 4 are bent at right angles to the plate, and extend downward a comparatively short distance in the form of tongues 7, having their ends inclined or beveled. The base is molded with threads about its lower end, adapted to engage an ordinary lamp socket. It has in its upper portion recesses 8 and 9, into which the terminal tongues 7 of the cap extend. A metal strip 10 is 60 molded in the base, having its upper end extending into the recess 9, and being slightly bent inward, and having its lower end 11 extending beyond the base and enlarged, as shown in Fig. 6, and bent over 65 the end of the base, covering the central area thereof, and forming the central terminal contact of the plug. Another metal strip 12 is molded into the other side of the base, having its inner end extended upward 70 in the recess 8 and slightly bent inwardly. Its outer end 13 extends to the side of the base, and is molded into the surface thereof, forming a longitudinal outer contact for 75 engaging the threaded socket of the ordinary electrical construction. This strip may be made of any width necessary or may even comprise a complete threaded shell, if desired.

Molded into the cap are metal members 100 14, diametrically disposed to the central opening 3. These members are formed with a terminal ball 15, and groove 16, as shown. Correspondingly placed in the base are recesses, in which spring metal members 17 105 are molded. These members are pressed out

of metal plates, to form a rounded receptacle, with converging edges. The metal is slit so that the receptacle is formed of a plurality of sections, or tongues, consequently the opening is resilient, and when the balls 15, are pressed toward the recess formed in this member 17, the tongues thereof spring outward and then close behind the ball to engage the groove 16. This construction is not new and is not itself a part of my invention, being known in the ordinary glove fastener. However, it furnishes a very desirable form of locking the parts together, permitting an easy locking and unlocking by relative movement of the cap and base. This means of attachment of cap and base is especially desirable where the plug is used with an electric fixture for table use. Frequently in such cases the plug is disconnected by giving the conductor cord a pull, which may be from any angle. The form of contact members 7, 10 and 12, making merely a wiping contact without engagement otherwise, prevents any catching or gripping of these parts when the cap is pulled off by a lateral force. Also the plug may be pushed out of engagement by the foot. Any movement that tilts the cap will tend to fulcrum it on an edge and will release the balls from their recesses.

The conductor wires are led through the opening 3 and engaged under the binding posts 6. When the cap is disengaged, the connections are fully exposed, and the conductors are easily removed. The base is molded to fit the ordinary socket, and when screwed therein it is securely held, the longitudinal metal strip 13 being in direct contact with the threaded shell of the socket, and the terminal portion 11 of the strip 10 being in direct connection with the central contact of the socket. When the cap is pressed into engagement with the base, the inclined tongues 7 contact with the ends of the spring contact members 10 and 12, which may also be bent or inclined, and as the tongues move inward this contact is constantly against increasing spring pressure, as will be obvious. The balls 15 are firmly engaged in the receiving members 17, and the cap is securely held in position for all normal purposes.

By this construction I have eliminated a large number of parts ordinarily used in separable attachment plugs, have made an integral base, which uses no screws, rivets or other securing means, and which may be formed by one molding operation. The contacts are positive, and there is nothing to come loose or to get out of order. The many advantages of the device in operation

as well as the economy of construction, and cheapness of manufacture will be apparent.

I claim:—

1. An attachment plug, comprising a cap member, and a base member, terminals carried by one of said members and contacts carried by the other, and inclosed means independent of the contact members for locking the cap and base together. 70

2. An attachment plug, comprising a cap member and a base member, terminals carried by the cap and contacts carried by the base, and inclosed means independent of the terminal and contact members for locking the cap and base together. 75

3. A separable attachment plug, comprising a cap member and a base member, terminals carried by the cap and extending into the base, contact members carried by the base and adapted to touch without gripping the terminal members therein, and inclosed means for locking the cap and base together comprising projections on one and spring-controlled recesses on the other. 80

4. A separable attachment plug, comprising a cap and a threaded base, the cap carrying terminal members adapted to extend into the base, and the base having recesses to receive said terminal members, and contact members molded in the base and adapted to engage without gripping said terminal members, the said contact members comprising metal strips extending to and overlying portions of the tip end and threaded side of the base, respectively. 85

5. A separable attachment plug, comprising a cap member and a base member, terminals carried by the cap, and contacts carried by the base, said contact members comprising a metal strip having one end molded in the side of the base and conformed to threads therein to form an outer contact, the other contact member being molded in the base with its outer end turned over the portion of the base to form a central terminal contact for the plug. 100

6. A separable attachment plug comprising a cap member and a base member, terminals carried by the cap and adapted to contact with similar members carried by the base, said contact members comprising metal strips molded in the base and adapted to form a threaded side contact and a central terminal contact, respectively. 110

In testimony whereof, I have hereunto set my hand.

CLARENCE A. VETTER.
